UNITED STATES PATENT OFFICE.

CHARLES L. MARSHALL, OF NEWARK, NEW JERSEY.

DESIGN FOR A LAMP-BURNER.

SPECIFICATION forming part of Design No. 30,333, dated March 14, 1899.

Application filed January 31, 1899. Serial No. 704,070. Term of patent 7 years.

To all whom it may concern:

- Be it known that I, CHARLES L. MARSHALL, a citizen of the United States of America, and a resident of Newark, in the county of Essex and State of New Jersey, have invented and produced a new and original Design for Lamp-Burners, of which the following is a specification, reference being had to the accompanying drawing, forming a part thereof.
- 10 The accompanying drawing represents a side elevation of a lamp-burner embodying my design.
- The leading features of my design are a cylindrical body located between two outwardly-flaring projecting portions rising therefrom and a short cylindrical portion below the lower projecting portion.
- 15 A represents the cylindrical body, and B B' the upper and lower outwardly-flaring projecting portions, respectively.
- 20 C represents the short cylindrical portion below the lower projecting portion.

The upper projecting portion rises from the cylindrical body in a curved form, as at b, and terminates in a flat or horizontal portion b'. 25 A chimney-gallery D surmounts the same. The lower projecting portion rises from the cylindrical portion in a curved form, as at b², and terminates in a return curved portion b³, below which is the short cylindrical portion 30 C, before mentioned.

Beads c c are arranged as shown, but do not constitute leading features of the design.

I claim—

The design for a lamp-burner, substantially 35 as herein shown and described.

In testimony whereof I hereby affix my signature in the presence of two witnesses.

CHARLES L. MARSHALL.

Witnesses:

HARRY E. DEY,
L. N. LEGENDRE.
